GEORGE E. A. HALLETT, OF DETROIT, MICHIGAN, ASSIGNOR TO GENERAL MOTORS RESEARCH CORPORATION, OF DETROIT, MICHIGAN, A CORPORATION OF DELAWARE

HYDRAULIC VALVE MECHANISM

Application filed April 11, 1927. Serial No. 182,935.

This invention relates to hydraulic operating mechanism and particularly to mechanism of this type designed to operate the valves of internal combustion engines. It is an improvement on the construction shown in my prior application, Serial No. 126,297 filed July 31st, 1926. In that application there is disclosed an hydraulic chamber containing fluid such as lubricating oil thru which motion is transmitted from an operating plunger to an operated plunger, the former being engaged by the usual push rod while the latter engages the valve stem. With this construction, the push rod carries the operating plunger with it on its upward stroke resulting in displacement of fluid in the hydraulic chamber which causes the operated plunger to be forced downwardly against the valve stem unseating the valve. To insure that the operating plunger will at all times follow the tappet, a light coil spring encircles the plunger and continuously urges it into engagement with the tappet. A similar spring is provided on the operated plunger.

While the described construction will operate satisfactorily, it has been found that the coil springs are a source of noise and to some extent interfere with valve operation, particularly when operated at speeds approaching their natural frequency of vibration.

Somewhat more satisfactory operation may be obtained by using torsion or leaf springs in place of coil springs, but I have found that the difficulty may be entirely overcome by employing a spring construction such that while constantly holding the plunger in contact with the valve or push rod, the spring is not periodically flexed or distorted during normal operation of the gear. This is accomplished by employing a leaf or bar spring pivoted at an intermediate or nodal point and having its ends engaging the respective plungers. The spring, when put in place, is given an initial stress such that it at all times tends to force the plungers downwardly into engagement with the tappet or valve stem. Were the plungers of equal displacement, the lengths of their strokes during nor-

mal operation of the gear would be equal and the rocker pivot would lie on a line midway between the plungers. However, it is usually found desirable to employ an operating plunger of greater displacement than the operated plunger thus enabling the use of a cam of lower lift and consequently quieter operation. In such designs, the stroke of the operating plunger is less than that of the operated plunger; consequently, the pivot of the rocker must lie nearer the former than the latter. As the location of the rocker pivot is thus fixed by the lengths of strokes of the plungers, I have, for lack of a better term, referred to the fulcrum point thus determined as a nodal point. It is obvious that this point may lie anywhere along a line drawn between the plungers parallel to their path of movement and spaced from the plungers in proportion to the lengths of their strokes.

The employment of a spring which, while in a constant state of stress is subject to little or no periodic flexing, permits working the spring near its elastic limit. This means that a lighter spring may be employed than would otherwise be required and consequently reduces cost. More important, by thus reducing the weight of the moving parts, less energy is consumed in operating the gear. The spring is preferably so mounted that it serves as a means to hold the plungers in their bores when removing the head to permit access to tappets and valves as when it is desired to grind the latter. It is obvious that this function may be performed by springs of other types or by non-resilient parts, if preferred.

In the drawings, Figure 1 is a vertical section thru a portion of an automobile engine equipped with hydraulic valve gear embodying my invention. Figure 2 is an enlarged view of the lower portion of the plungers and the rocker spring, as shown in Figure 1, but with the parts removed from the engine.

Figure 3 is a section on line 3-3 of Figure 2. Figure 4 is a fragmentary view showing modified forms of plungers and rocker spring. Figure 5 is a plan view of the spring of Figure 4.

Reference character 2 indicates one of the valves of an internal combustion engine of the overhead valve type, the one illustrated being the well-known Buick design. 4 indicates the cam shaft and 6 the tappet held in engagement with the cam shaft by the coil spring 8. The upper end of the tappet 6 engages the operating plunger 10 while the upper end of the valve stem is engaged by 10 the operated plunger 12. These plungers reciprocate in guideways communicating with hydraulic chamber 14. This chamber is supplied with oil from reservoir 16 thru inlet valve 18 shown as of the leaf spring 15 type. The specific arrangement of the hydraulic mechanism in so far as it differs from that shown in my prior application and is not claimed herein is described and claimed in an application of John O. Almen. I have 20 shown at 20 a plug thru which oil may be supplied to the valve chamber and thru which air may be discharged when desired.

In the construction shown, the guides for the plungers 10 and 12 and the reservoir 16 25 are formed in a casting 22 which is in the form of a head superposed on the usual cylinder head. The hydraulic chamber 14 is formed in a cover 24 bolted to the head, 22. A fork 26 projects downwardly from the 30 underside of the reservoir 16 and serves as a fulcrum for my rocker spring, to be later described.

It is to be understood that a separate chamber 14, as well as operating and operated 35 plungers, is provided for each of the valves. The cover 24 may be divided by suitable partitions to provide the separate reservoirs. The reservoir 16 is designed to serve a number of chambers and I have shown it supplied 40 with oil from a suitable source, such as the crankcase, thru conduit 28. The oil is pumped into the chamber by the usual pump serving for the lubrication of the engine. To insure against the draining of the reservoir 45 16 when the engine is idle, a suitable check valve may be provided in the conduit 28.

My improved spring is shown at 30. As best shown in Figure 3, it comprises a transverse portion 32 held in the fork 26 by any 50 suitable means, such as a cotter pin 34. The portion 32 is provided with return bent portions 36 and 38 terminating in longitudinal portions 40 and 42. The portion 40 has a 55 rocking and sliding fit in an aperture 44 formed in an extension of the operating plunger 10, while the portion 42 is similarly fitted in an aperture 46 in an extension of the operated plunger 12.

It will be apparent that the engagement 60 of the ends of the spring with the plungers prevents them dropping out of their guides.

Figure 2 shows the relation of spring and plungers when the head 22 is removed from 65 the engine. It will be noted that the spring

is here shown in its free or unstressed position and it will be observed that the portions on opposite sides of the transverse portion 32 do not lie in the same plane but extend at a slight angle to each other. When the head 70 is fitted on the engine, the spring 30 is stressed so that its oppositely extending portions 36-40 and 38-42 lie in the same plane. The effect of this is to cause the spring to 75 at all times hold the plungers in engagement with the tappet and valve respectively. 75

It will be noted that the fork 26 is not located midway between the plungers. It is, however, located along the "nodal" line determined by the relative displacements of the 80 plungers as previously described; thus, since the plunger 10 is of greater displacement, the nodal line lies nearer that plunger than the operated plunger. The result of this arrangement is that while the spring at all 85 times urges the plungers downwardly and thus causes them to follow up the tappet and valve respectively, the spring is not stressed as a result of the up and down motion of the parts but merely rocks about its axis. There 90 is no periodic stressing of the spring over long periods with the possibility of this period approaching the natural period of vibration of the spring. The spring is consequently silent in operation. At the same 95 time, the spring serves as a convenient means for attaching the plungers to the head so that the entire hydraulic apparatus may be removed from the engine without any possibility of oil being spilled. 100

It may be mentioned that for short intervals the spring will be subjected to periodic flexing; thus should the chamber 14 be completely or partly empty of oil the motion of the operating plunger will be transmitted only in part, if at all, to the operated plunger, the result being that the spring 30 will be flexed about its axis. However, it will continue to urge the operating plunger outwardly of the chamber causing an effective pumping action which, after a few strokes, will draw oil into the chamber from the reservoir 16. When the chamber 14 is filled with oil, the spring 30 will again perform a simple rocking movement. 110

In Figures 4 and 5 I have illustrated a slightly modified construction. Here the spring 50 is in the form of a flat leaf, normally distorted as shown in Figure 4, but forced to lie in a single plane when the gear 120 is mounted on the engine. 52 indicates an angle bracket secured to the bottom of the reservoir 16, having its downwardly extending arm 54 perforated as at 56 to receive the spring and provide a fulcrum therefor. The ends of the spring are notched as at 58 to fit in annular grooves or behind annular shoulders 60 provided at the lower ends of the pistons. The operation of this construction 125 130

of spring is identical with the operation of the form shown in the preceding figures.

The invention herein disclosed may take various other forms and the claims consequently are not limited to the precise design shown.

I claim:

1. The combination of an operating plunger, an operated plunger, an hydraulic chamber containing a body of fluid interposed between said plungers for transmitting movement from one to the other and a rocker spring engaging said plungers, said spring being normally under stress so as to continuously urge said plungers outwardly of the chamber.

2. In the combination as defined in claim 1, said plungers being of unequal displacement, and the axis of said rocker spring lying nearer the piston of greater displacement so that the normal action of the spring is purely a rocking action.

3. In the combination as defined in claim 1, the axis of said rocker spring being located at a nodal point determined by the length of stroke of said plungers so that there is no periodic distortion of the spring in normal operation.

4. Hydraulic operating mechanism comprising an operating part, an operated part, an hydraulic chamber containing a body of fluid interposed between said parts for transmitting motion from one to the other by displacement of the fluid in the chamber and common means for yieldingly urging said parts outwardly of the chamber.

5. Valve mechanism comprising a valve, a tappet, an operating plunger engaged by the tappet, an operated plunger engaged by the valve, an hydraulic chamber containing a body of fluid interposed between said plungers and a spring engaging said plungers and normally urging them outwardly of the chamber.

45 6. In the combination as defined in claim 5, said spring being in the form of a rocker pivoted at a nodal point determined by the length of stroke of the plungers so that the normal action of the spring is purely a rocking action.

50 7. In the combination as defined in claim 5, said spring having its ends connected to said plungers and provided with an intermediate portion forming a fulcrum and a bearing for said intermediate portion.

8. The combination of a motor comprising a cylinder, a piston in the cylinder, a valve for the cylinder, a push rod for operating the valve, hydraulic devices for transmitting movement from the push rod to the valve comprising a head adapted to be removable attached to the engine and formed to provide an hydraulic chamber having guides communicating therewith, plungers in said guides, one of said plungers engaging said

tappet and the other said valve, and means secured to said head and engaging said plungers to retain the plungers in the guides upon removal of the head from the engine.

9. In the combination as defined in claim 8, said means comprising a resilient member normally urging the plungers into engagement with said tappet and valve respectively.

10. In the combination as defined in claim 8, said means comprising a rocker spring having its ends in engagement with said tappet and valve respectively, said spring being normally stressed to hold said plungers in engagement with the tappet and valve respectively.

11. In the combination as defined in claim 8, said means comprising a rocker spring having its ends in engagement with said tappet and valve respectively, said spring being normally stressed to hold said plungers in engagement with the tappet and valve respectively, and the rocker axis being located at a nodal point determined by the lengths of the strokes of the plungers.

12. A torsion spring having an intermediate transverse portion forming a pivot, return bent portions at the ends of the intermediate portion, said portions terminating in longitudinal extensions adapted for connection to suitable parts.

13. In the combination as defined in claim 12, said spring having a slight camber.

14. Hydraulic valve operating mechanism comprising a valve, a spring for urging the valve against its seat, a tappet, a cam, a spring for holding the tappet against the cam, an operating plunger engaged by the tappet, an operated plunger engaged by the valve, an hydraulic chamber containing a body of fluid interposed between said plungers, and a rocker spring having its ends engaging said plungers and being normally assembled in distorted position so that it yieldingly urges at least one of said plungers against its contacting member.

15. In the combination as defined in claim 14, said rocker spring being pivoted at a point intermediate the plungers determined by the relative extent of movement of the operating and operated plungers so that it is subject to pure rocking action only during the operation of the valve gear.

16. In valve operating gear the combination of a plurality of reciprocating parts and a torsion spring arranged between said parts for transmitting motion from one to the other, said spring comprising a pair of arms and an intermediate torsional portion of resilient material arranged to transmit torsional strain from one arm to the other.

17. The combination of a pair of reciprocating parts, a torsion spring confined for pivotal movement about its torsional axis, said spring having its ends engaging said parts

for transmitting motion from one to the other.

18. The combination of a pair of reciprocating parts, a torsion spring confined for movement about its torsional axis, said spring being normally stressed so as to exert pressure on said parts and having its ends engaging said parts for transmitting motion from one to the other.
19. In valve operating mechanism, the combination of an operating part, an operated part, a spring member including a pivotally mounted transversely extending torsional portion and oppositely extending ends in engagement with said parts for transmitting motion from one to the other, said transversely extending torsional portion being formed of spring material and adapted to transmit torsional strain from one end of the member to the other.

In testimony whereof I affix my signature.
GEORGE E. A. HALLETT.
